CLAIM

The ornamental design for a snuffer lid for a miniature fireplace, as shown and described.

DESCRIPTION

FIG. 1 is a top perspective view of the snuffer lid for a miniature fireplace of the Applicant's invention;

FIG. 2 is a bottom perspective view thereof;

FIG. 3 is a side elevational view thereof;

FIG. 4 is a side elevational view thereof, rotated 60 degrees relative to the view shown in FIG. 3;

FIG. 5. is a top plan view thereof; and,

FIG. 6 is a bottom plan view thereof.

Where included, broken lines showing environment or structure are for illustrative purposes only and form no part of the claimed design.

1 Claim, 4 Drawing Sheets
